[57] **CLAIM**

The ornamental design for a container for developed photographic film, as shown and described.

DESCRIPTION

FIG. 1 is a front, top and side perspective view of a container for developed photographic film showing our new design;

FIG. 2 is an front elevational view thereof;

FIG. 3 is a rear elevational view thereof;

FIG. 4 is a top plan view thereof;

FIG. 5 is a bottom plan view thereof;

FIG. 6 is a side elevational view thereof from the right of FIG. 2, the side opposite that shown in FIG. 6 being the mirror image thereof;

FIG. 7 is a cross sectional view thereof on the line A—A of FIG. 2; and,

FIG. 8 is a view similar to FIG. 6 but wherein a lid for covering a film passage slit is open.

FIG. 1

FIG. 2

FIG. 3

FIG. 4

FIG. 5

FIG. 6

FIG. 7

FIG. 8
